[57] CLAIM

The ornamental design for a carrying case, as shown and described.

DESCRIPTION

FIG. 1 is a perspective view of a carrying case showing our new design;

FIG. 2 is an end elevational view of the carrying case, taken from the lefthand side of FIG. 1, the opposite end being substantially a mirror image thereof;

FIG. 3 is a front elevational view of the carrying case;

FIG. 4 is a plan view thereof;

FIG. 5 is a rear elevational view thereof; and,

FIG. 6 is a bottom view thereof.

FIG.1

FIG. 2

FIG. 3

FIG. 4

FIG. 5

FIG. 6
